GRINDING MACHINE

Frederick S. Haas, Cincinnati, Ohio, assignor to
 Cincinnati Grinders Incorporated, Cincinnati,
 Ohio, a corporation of Ohio

Application April 2, 1931, Serial No. 527,252

7 Claims. (Cl. 51—166)

This invention relates to improvements in machine tool structures and especially to improvements in a grinding machine.

One of the principal objects of the present invention is the provision of improved means for driving laterally shiftable spindles or shafts, such as a grinding wheel spindle.

Another object of the invention is the provision of an improved floating, flexible drive from a prime mover or initial power source to a shiftable spindle which will maintain the proper driving tension in the flexible drive means.

Another object of the invention is the provision of a flexible or belt drive mechanism in which the necessary tension is maintained and adjusted without the use of idler pulleys, gears, or other tensioning mechanism.

Another object of the invention is the provision of improved means for supporting and driving a series of fluid pumps, each having a function independent of one another.

A further object of the invention is the provision of an improved structure for assembling or disassembling a plurality of individual units, each having its own power shaft and each shaft being driven from a common power source.

A still further object of the invention is the provision of improved means for mounting a plurality of units and providing a drive from the driving shaft of one unit to the driving shaft of the next unit whereby certain units may be eliminated or additional units employed and the coupling between readily attained.

Other objects and advantages of the present invention should be readily apparent by reference to the following specification considered in conjunction with the accompanying drawings and it is to be understood that any modifications may be made in the exact structural details there shown and described, within the scope of the appended claims, without departing from or exceeding the invention.

In the drawings:

Figure 1 is a top plan view of a grinding machine embodying the improvements of this invention.

Figure 2 is an end elevational view of the machine shown in Figure 1 as seen from line 2—2 on said Figure 1.

Figure 3 is a fragmentary sectional view taken on line 3—3 of Figure 2.

Figure 4 is a fragmentary sectional view taken on line 4—4 of Figure 2.

Throughout the several views of the drawings

similar reference characters are employed to denote the same or similar parts.

A device of this invention may comprise a bed or base 10 having formed at the upper end thereof ways 11 and 12 for the work supporting table 13 translatable longitudinally of the bed 10 and guided by the ways 11 and 12. The table 13 has adjustably secured thereto headstock 14 and tailstock 15 for suitably supporting and rotating the work 16. Any known means may be employed for translating the table 13.

The bed 10 is further provided with ways 17 extending in a direction transversely to the ways 11 and 12, for the grinding wheel carriage 18 which rotatably supports a spindle 19 having secured thereto the grinding wheel 20. The carriage 18 and parts carried thereby are adapted to be actuated by means of a screw 21 rotated by any known cross feed structure which terminates in the cross feed ratchet 22.

In the past, idler gears, pulleys or the like, have been employed for maintaining the proper driving tension in a belt or other flexible drive, utilized for rotating the spindle 19 and the grinding wheel 20. This has entailed a considerable expense and annoyance which has been eliminated by the present invention. The spindle 19 is driven from a suitable prime mover here shown as an electric motor 23 carried by base or bed 10 and having a motor shaft 24 to which is secured driving pinion 25. A silent chain 26 or the like, extends about the pinion 25, as well as about a pinion 27 fast on one end of a countershaft 28. This countershaft 28 is suitably journaled in antifriction bearings 29 and 30 carried in bearing sleeve 31. At the other end the shaft 28 has secured to it a pulley here shown as a multiple belt sheave 32. The belts or transmission members 33 extend from the sheave 32 up around pulley or sheave 34 secured on the outer end of the spindle 19.

The bearing sleeve 31 is mounted for swinging or oscillating movement toward and from the axis of the spindle 19 for which purpose it has extending therefrom arms 35 and 36 each provided with a bore in its free end and journaled on trunnions 37 and 38 extending from a bracket 39. The bracket 39 is formed integral with a suitable plate 40 secured by bolts 41 extending through elongated slots 42 to the pad or bearing face 43 integral with the bed 10. The plate 40 substantially covers an opening into the interior of the bed 10 through which the bracket 39 and parts carried thereby are let. By reference to Figure 2, it will be noted that the plate 40 is cut 110

- away as at 40a and the said cut away portion forms with the opening 40b an unrestricted passage through which the countershaft 28 protrudes and which passage permits the vertical 5 swinging or oscillation of the bearing sleeve 31. In order to maintain the proper distance between the axes of spindle 19 and shaft 28 there is provided an adjustable link connection. The connection includes plates 44 and 45, each having a threaded socket 46 and 47 receiving opposite ends of turn buckle screw 48. The plates 46 and 47 are respectively secured to the turned trunnion portion 49 on the grinding wheel carriage 18 and a trunnion 50 on the end of bearing sleeve 31.
- By reference to Figure 2, it will be noted that movement of the carriage 18 on the ways 17 will tend to increase the distance between the axes of spindle 19 and shaft 28 but, due to the connection between these shafts, said movement of the carriage will oscillate the sleeve 31 about the axis of the trunnions of bracket 39 thereby at all times maintaining the same driving tension in the belts or transmission members 33. In order to properly tension the transmission chain 26 the plate 40 is adjustable in the direction of extent of the said belt 26 by loosening the clamp bolts 41 and shifting said plate at which time the bolts 41 are again tightened.
- The bracket 39 is provided interiorly thereof with bearings 51 and 52 for a pump shaft 53 journaled therein. This shaft 53 may be termed the main pump shaft and it has secured to it a pinion 54 about which is trained a gear chain 35 deriving power from a gear 56 secured on the countershaft 28. Rotation of the countershaft 28 will, therefore, rotate the main pump shaft 53 for driving the cams 57 thereon for actuating pump pistons 58. The pump pistons 58 are enclosed in a suitable casing 59 secured to the bracket 39. The said main pump is utilized for delivering fluid under high pressure for actuating various units of a machine tool organization, such as the wheel head or carriage, for example.
- Secured to the trunnion 38 is the housing or casing 60 of a twin gear booster pump having a portion thereof extending into a counterbore 61a of the bracket 39. The pump 60 is provided with a pump shaft 61 extending beyond the ends of said pump. One end 62 of the shaft 61 is journaled in a socket formed in the adjacent end of the main pump shaft 53 and the said end of the pump shaft 53 has a slot 63 formed therein receiving a pin 64 extending from opposite sides of the shaft 61. From this it will be seen that rotation of the shaft 53 will, through the slot and pin connection, drive the shaft 61. Also, it will be apparent that the axial alignment of the shafts need not be accurate within exceedingly fine limits since sufficient play may be provided without interfering with the driving connection.
- Secured to the pump 60, as by means of bolts or screws 64a, is the housing 65 of an additional fluid pump 66 which may be employed for circulating the coolant or cutting compound of a machine tool organization. The pump 66 is also provided with a shaft 67 extending beyond the housing 65 at the end adjacent the pump 60 and the said end of the shaft 67 is provided with a socket 68 in which is received the adjacent end of shaft 61. A slot 69 is formed in the socketed end of shaft 68 and has extending therethrough a pin 70 protruding from the shaft 61. It will be apparent that the shaft 67 is rotated from the shaft 61 and, similar to the alignment of
- shafts 53 and 61, the shaft 67 need not be in absolute axial alignment since the pin and slot connection will permit sufficient misalignment within commercial production limits so that a proper driving connection may be had.
- Secured to the trunnion 37 of the bracket 39 is another fluid pump 71 having a portion 72 thereof extending into a counterbore 73 formed in the said trunnion 37. This pump 72 may be employed for lubricating the moving parts of a machine tool organization, such as the guideways, shafts, or the like. A pump shaft 74 is included in the pump 72 and has its end adjacent the end of the main pump shaft 53 extending beyond the confines of the pump and the said end is received in a socket 75 formed in the main pump shaft 53. A pin and slot connection 76 affords the driving of the shaft 74 from the main pump shaft 53 and, similar to the other pin and slot connection, a slight misalignment will be amply compensated for.
- It is to be understood that if desired, certain pumps may be eliminated when not needed without in anywise interfering with the general assembly of the parts and the efficient operation thereof. It is also to be understood that additional pumps or units, each having its own driving shaft, may be supplied and connected with the ends of the driving shafts of other units through a pin and slot coupling. It will be noted that the bracket 39 forms the trunnions for the swinging bracket 31 but is itself held against any movement thereby preventing any interference in the drive of the parts and their efficient operation.
- The attachment of the plates 44 and 45 to the trunnions 49 and 50 is of the split connecting rod bearing type, having the parts joined on a line in the same plane as the axes of the spindle 19 and shaft 28. The same type of connection may be effectively used for connecting the ends of the arms 35 and 36 and the trunnions 37 and 38.
- To avoid possible injury to the operator or persons in the vicinity of the machine the belts or transmission members 33 are enclosed within suitable guards. As shown in Figure 3, the guards comprise an upper section 77 secured by bolts or the like 78 to the portion of plate 44 extending around the trunnion 29, while the section 79 of the guard is secured by bolts 80 to the portion of the plate 45 extending around the trunnion 50. The adjacent inner ends 81 of the guards 77 and 79 telescope within one another so that adjustment of the turn buckle screw 48 to vary the distance between the axes of spindle 19 and shaft 28 automatically adjusts the guards 130 without exposing any part of the transmission mechanism.
- What is claimed is:
1. In a device of the class described the combination of a bed or support, a grinding wheel carriage carried by said bed or support for movement transversely thereof, a spindle journaled in the carriage, means for rotating said spindle including a prime mover, a countershaft, flexible power transmission means between the prime mover and countershaft, flexible transmission means between the countershaft and spindle, an adjustable plate carried by the bed and having trunnions projecting from opposite sides thereof, arms journaled on said trunnions and supporting the countershaft for floating movement about the axis of the trunnions, means pivotally mounted opposite ends concentrically with the axis of the spindle and countershaft for definitely spacing the said axes of the counter- 150

- shaft and spindle from one another to tension the flexible transmission means therebetween, and means for locking the plate in adjusted positions in the direction of extent of the flexible transmission means between the prime mover and countershaft to tension said transmission means. 5
2. In a machine of the class described the combination of a bed or support, a grinding wheel carriage carried thereby and movable transversely thereof, a spindle journaled in said carriage, means for actuating the carriage relative to the bed, a plate carried by the bed, a bracket supported by the plate, a trunnion projecting from one side of the plate, a trunnion projecting from 10 the other side of the bracket, a bearing sleeve having arms extending therefrom and journaled for oscillating movement about the trunnions, a countershaft in said bearing sleeve, flexible transmission means between the countershaft and spindle, and means pivotally mounted at opposite ends concentrically with the axis of the spindle and countershaft for definitely spacing the said axes of the spindle and countershaft from one another to tension the flexible transmission 15 means during the transverse adjustment of the grinding wheel carriage.
3. In a machine of the class described the combination of a bed or support, a grinding wheel carriage carried thereby and movable transversely thereof, a spindle journaled in said carriage, means for actuating the carriage relative to the bed, a plate carried by the bed, a bracket supported by the plate, a trunnion projecting from one side of the plate, a trunnion projecting from 20 the other side of the bracket, a bearing sleeve having arms extending therefrom and journaled for oscillating movement about the trunnions, a countershaft in said bearing sleeve, flexible transmission means between the countershaft and spindle, means definitely spacing the axes of the spindle and countershaft from one another to tension the flexible transmission means during 25 the transverse adjustment of the grinding wheel carriage, a prime mover, flexible transmission means between the prime mover and countershaft, and means for adjusting and clamping the plate and bracket in the direction of extent of the transmission means between the prime mover and countershaft for tensioning said transmission means. 30
4. In a machine of the class described the combination of a bed or support, a grinding wheel carriage carried thereby and movable transversely thereof, a spindle journaled in said carriage, means for actuating the carriage relative to the bed, a plate carried by the bed, a bracket supported by the plate, a trunnion projecting from one side of the plate, a trunnion projecting from 35 the other side of the bracket, a bearing sleeve having arms extending therefrom and journaled for oscillating movement about the trunnions, a countershaft in said bearing sleeve, flexible transmission means between the countershaft and spindle, means definitely spacing the axes of the spindle and countershaft from one another to tension the flexible transmission means during 40 the transverse adjustment of the grinding wheel carriage, a prime mover, flexible transmission means between the prime mover and countershaft, and means for adjusting and clamping the plate and bracket in the direction of extent of the transmission means between the prime mover and countershaft for tensioning said transmission means. 45
5. In a machine of the class described the combination of a bed or support, a grinding wheel carriage carried thereby and movable transversely thereof, a spindle journaled in said carriage, means for actuating the carriage relative to the bed, a plate carried by the bed, a bracket supported by the plate, a trunnion projecting from one side of the plate, a trunnion projecting from 50 the other side of the bracket, a bearing sleeve having arms extending therefrom and journaled for oscillating movement about the trunnions, a countershaft in said bearing sleeve, flexible transmission means between the countershaft and spindle, means definitely spacing the axes of the spindle and countershaft from one another to tension the flexible transmission means during 55 the transverse adjustment of the grinding wheel carriage, a fluid pump mechanism including a pump shaft carried by the bracket, and transmission means between the countershaft and pump shaft for driving the latter from the former. 60
6. In a machine of the class described the combination of a bed or support, a grinding wheel carriage carried thereby and movable transversely thereof, a spindle journaled in said carriage, means for actuating the carriage relative to the bed, a plate carried by the bed, a bracket supported by the plate, a trunnion projecting from one side of the plate, a trunnion projecting from 65 the other side of the bracket, a bearing sleeve having arms extending therefrom and journaled for oscillating movement about the trunnions, a countershaft in said bearing sleeve, flexible transmission means between the countershaft and spindle, means definitely spacing the axes of the spindle and countershaft from one another to tension the flexible transmission means during 70 the transverse adjustment of the grinding wheel carriage, a fluid pump mechanism including a pump shaft carried by the bracket, transmission means between the countershaft and pump shaft for driving the latter from the former, a second pump adapted to be secured to the bracket or plate including a rotatable shaft, and means for coupling the rotatable shaft with the pump shaft. 75
7. In a device of the class described the combination of a bed, a grinding wheel carriage carried thereby and shiftable relative thereto, a spindle journaled in the carriage, means for actuating the carriage transversely of the bed, a bearing sleeve, a countershaft journaled in said sleeve, means pivotally mounting the sleeve on the bed, 80 flexible transmission means between the countershaft and spindle, a trunnion formed on the carriage concentric with the spindle, a trunnion formed on the sleeve concentric with the axis thereof, a plate carried by each trunnion and 85 each plate having a threaded socket portion formed therein, and a threaded turn buckle connection received in the threaded socket portions of the plates for definitely spacing the axes of the spindle and floating countershaft from one another to tension the flexible transmission means 90 therebetween during the transverse adjustment of the grinding wheel carriage. 95

FREDERICK S. HAAS. 145
